(57) **CLAIM**

The ornamental design for a camera component, as shown and described.

DESCRIPTION

FIG. 1 is a front perspective view of the camera component of the present invention;

FIG. 2 is a rear perspective view of the camera component of FIG. 1;

FIG. 3 is a front elevational view of the camera component of FIG. 1;

FIG. 4 is a rear elevational view of the camera component of FIG. 1;

FIG. 5 is a left-side elevational view of the camera component of FIG. 1;

FIG. 6 is a right-side elevational view of the camera component of FIG. 1;

FIG. 7 is a top plan view of the camera component of FIG. 1; and,

FIG. 8 is a bottom plan view of the camera component of FIG. 1.

The broken line showing on the drawing disclosure is for illustrative purposes only and forms no part of the claimed design.
